UNITED STATES PATENT OFFICE.

EDWARD G. MEYERS, OF CINCINNATI, OHIO.

AUTOMATIC MARKING MACHINE.

Application filed May 31, 1921. Serial No. 473,689.

To all whom it may concern:

Be it known that I, EDWARD G. MEYERS, a citizen of the United States, residing in the city of Cincinnati, county of Hamilton, 5 and State of Ohio, have invented certain new and useful Improvements in Automatic Marking Machines, of which the following is a specification.

My invention relates to automatic marking machines, and more particularly to those employed for making imprints on fabrics and other materials by the use of inks, such as those containing silver nitrate and afterwards made visible by the action of a fixing 15 member embodied within the machine.

The inks have for their main constituent silver nitrate, and are liquids, soluble in water. The silver nitrate however, can be reduced to finely divided metallic silver, and 20 thus made visible by the action of heat or high intensity light waves. The inks in this form are very dark in appearance and insoluble in ordinary fluids. The paper, fabric, wood or other material which it is 25 desired to mark is herein referred to as the material.

My improved marking machine is not limited to the use of silver nitrate inks only, but is readily adapted for marking with 30 slow drying inks, the fixing member being utilized to rapidly dry the impression made. I have however herein described the operation of my invention in connection with silver nitrate inks although any other ink 35 may be used.

One of the objects of my invention is the imprinting and insoluble fixing on, and into fabric, paper, wood and other materials, trade marks, designs and marks of ownership 40 and identification, or such other markings as may be desired.

Another object of my invention is to provide a means whereby the imprints are rapidly and automatically made and driven into 45 the material by means of a fixing element, utilizing heat.

Another object is to regulate the quantity of marking ink used in marking the imprint and thereby controlling the depth of penetration for varying thicknesses and qualities of material.

Another object is to regulate the length of application of the fixing member employed in driving into and indelibly fixing the im-

pression made on the material, and also to 55 control the degree of heat employed therefor.

A further object is to avoid injury to the material by the printing die and the fixing member and to the die and fixing member 60 themselves.

My invention consists in the provision of a machine embodying mechanism for automatically imprinting on various material, suitable designs or other markings by the use 65 of ink, and further in mechanism for treating the impression made so as to prevent its subsequent eradication.

My invention further consists in the mechanism embodying an automatically actuated 70 die corresponding to the markings desired and in the means for conveying the ink thereto and also in the mechanism by which the duration of contact of the die with the material is varied whereby the penetration of the 75 ink is controlled.

My invention further consists in an automatically actuated fixing element, for reducing the ink in the impression made to a compound insoluble in ordinary fluids and 80 also in the means for varying the duration of contact of the fixing element with the impression.

My invention further consists in a yielding support for the material, so as to avoid 85 injury to the material and also to the die and fixing element.

My invention further consists in the parts and combination and arrangement thereof as herein described and claimed. 90

In the drawings:

Fig. 1 is a front elevation of my improved machine.

Fig. 2 is a similar view of the motor and driving mechanism for my improved machine. 95

Fig. 3 is a side elevation of my improved machine, with the frame partly broken away, and in section on the line 3—3 of Fig. 1.

Fig. 4 is a plan view of the same with 100 the upper part of the frame partly broken away to expose the interior mechanism.

Fig. 5 is a horizontal cross-section taken on the line 5—5 of Fig. 3.

Fig. 6 is a vertical cross-section taken on 105 the line 6—6 of Fig. 3.

Fig. 7 is a similar view taken on the line 7—7 of Fig. 3.

Fig. 8 is a vertical section taken on the line 8—8 of Fig. 6 illustrating the cam for actuating the fixing member.

Fig. 9 is a similar view taken on the line 5 9—9 of Fig. 6 illustrating the cam for actuating the die.

Fig. 10 is a vertical section taken on the line 10—10 of Fig. 6 showing the hold down cam.

10 Fig. 11 is a perspective view of the ink distributing plate.

In my improved marking machine, the material to be marked is first placed on a support 20, yieldably mounted in a part of a 15 main frame 21 in a manner hereafter more particularly described.

A suitable die 22 having raised imprinting projections thereon is caused to automatically contact an inking pad 23 of fibrous 20 materials such as felt and then automatically brought into contact with the material placed on the support. The die has beveled edges 24, which coact with dovetails 25 of a 25 die carrier 26. In this way the die is readily secured to the carrier. I prefer to actuate the die in such a manner as to have its imprinting face turned upward when in contact with the inking pad, and turned downward when in contact with the material. To accomplish this the die is caused 30 to have both a rotary and vertical movement. To this end a drive shaft 30 is journaled in a permanent bearing 31 in the main frame and a removable bearing 32 held in a bore 35 33 of the main frame by a set screw 34. A grooved driving pulley 36 is journaled about a reduced end 37 of the drive shaft, and is held against lateral movement as by being received between a shoulder 38, and a washer 40 40 clamped against a second shoulder 40 by a locknut 41. The pulley is made to act as a fly wheel by forming the rim 42 of relatively 45 heavy cross section.

The pulley is constantly driven by a motor 45 the motor shaft 46 of which is extended, and journaled in bearing 47 of a reduction gear casing 48. The reduction gear comprises a worm 49 secured to the rotor shaft, and meshing with a wormwheel 50 50 on a shaft 51 journaled in bearings 52 of the reduction gear casing. A grooved pulley 53 is secured to the shaft 51 outside of the casing and has a belt 54 passing thereabout and also about the grooved driving 55 pulley 36. In this manner the driving pulley is caused to rotate at a relatively low speed.

The main frame is preferably so proportioned as to admit of its being placed on a 60 bench in such manner as to bring the material support to a proper working height. I have herein however, illustrated my improved machine mounted on a pedestal 60 to which the main frame is secured by bolts 65 61. The pedestal has a flaring base 62

whereby greater stability is secured. The upper end of the pedestal has a bracket 63 integrally formed therewith to which the reducing gear casing is secured by bolts 64. The reduction gear casing has a bracket fixed 70 thereon to which the motor is secured by bolts 65.

The drive shaft 30 is adapted to either receive constant rotation or a single revolution at the will of the operator. Thus 75 68 is a single revolution clutch and comprises a hub 69 movable endwise on the shaft 30 between the bearing 31 and the driving pulley 36. A key 70 in the shaft coacts with a keyway 71 on the hub to hold the same against relative rotation on the shaft. The hub further has pins 72 secured therein on the side facing the pulley. Pins 73 are firmly secured in the driving pulley adapted to coact with the pins 72. The hub 69 is normally urged toward the pulley by a spring 74, which compels the pins 72 to engage the pins 73, whereby rotary motion is imparted to the drive shaft.

Means is provided to enable the operator 90 to cause the shaft to rotate but one revolution at a time. Thus a plunger 76 has vertical movement in a bearing 77 secured to main frame, and also in a bearing 78 on the pedestal. The plunger is urged towards the periphery 79 of the hub 69 by a spring 80 received between the bearing 78 and a collar 81 secured to the plunger by a pin 82. The end of the plunger is adapted to coact with a groove 85 having a cam surface 86 extending in the direction of the driving pulley. A treadle 87 pivoted on a screw 88 has connection with the plunger as by a connecting rod 89, having articulations 90 with the plunger, and articulations 91 with the treadle. The treadle has a step 92 at its outer end adapted to receive the foot of the operator. The driving pulley 36 is driven in the direction of the arrow a. (See Fig. 1.) When the operator places his foot on the treadle 110 and forces it downward, the plunger 76 is withdrawn from the groove 85, thereby permitting the spring 74 to urge the hub 69 towards the driving pulley. The pins 72 will then make contact with the pin 73 on the driving pulley and thereby rotate the drive shaft. While this is being accomplished the end of the plunger 76 is riding on the periphery 79 of the hub. Toward the final part of one revolution, the plunger 76 115 enters the groove 85, the cam surfaces coacting therewith to draw the hub away from the pulley, disengaging the pins 72 and 73, and thereby stopping rotation of the drive shaft.

A cam 95 for actuating the die has a hub 96 thereon, which has a bore 97 therein through which the drive shaft passes. A key 98 in the shaft provides driving connection for the cam as by being received in a key- 130

way 99 in the hub 96. The drive shaft 30 is fitted in the bore 97 in such a manner as to be readily withdrawn therefrom. For securing the cam against endwise movement 5 a set screw 100 is threaded into the hub and contacts the shaft.

The cam 95 has a concentric surface 101 and a depression 102 formed by the downwardly sloping surface 103 and the upwardly sloping surface 104. A follower 105 has vertical movement in a hole 106 of a lug 107 on the main frame. A roller 108 is adapted to coact with the periphery of the cam 95 and is journaled on a stud 109 having 15 threaded connection 110 with the follower. The roller 108 is preferably held against endwise movement as by being received in a slot 111 of the follower. A connecting rod 115 is secured to the follower as by threaded 20 connection 116 held in place by lock-nut 117. The connecting rod has endwise movement in a bearing 118 of the main frame. The follower is held against rotary movement, as by set screw 119 threaded into the bearing 118, the end of which enters a keyway 25 120 of the connecting rod. The follower is urged toward the cam as by having a spring 121 received between the bearing 118 and an adjusting collar 122 held in adjusted position by a set screw 123. The upper end of the connecting rod has a knuckle 124 secured thereto which has articulation by a pin 125 to a rockable lever 126. The rockable lever has one end thereof journaled 30 about a pin 127 held in place by cotter pins 128 in a lug 129. The other end of the rockable lever has a cross shaft 132 received in a hole 133.

The die carrier 26 is guided laterally by 40 guides 136 forming part of a die head 137 and is also rockable about a shaft 135. The shaft is journaled in a bearing 138 of the die carrier and is held in place by a bearing cap 139 secured by bolts 140. The shaft 135 has vertical movement in guide slots 142 in the side guides 136. Rollers 141 journaled about the shaft aid its easy movement in the slots. The shaft projects beyond the slots and has reduced ends 143 about which 50 the ends of links 144 are received. The links are held in place as by having a washer 145 and the lock-nut 146 received over the threaded portion 147 of the reduced ends. The other ends of the links are received about reduced ends 150 of the cross shaft 132 and are held in place by locknuts 151 having threaded connections 152 thereon. The links are spaced from the rockable lever 126 as by sleeves 153 received about the cross shaft. Vertical movement is imparted to 60 the shaft 135 by the roller 108 entering the depression 102 of the cam 95 on the drive shaft under pressure exerted by the spring 121. Through the medium of the connecting rod 115, rocking motion is imparted to

the rockable lever 126, which in turn imparts vertical movement to the shaft by the links 144.

Means is provided whereby the die carrier 26 with the die thereon is given a rocking 70 movement to the extent of a half revolution, as well as the vertical movement previously described. Thus depending flanges 155 are formed on the ends of the die carrier and bear against the guides 136. A heart shaped 75 cam 156 is formed on each of the depending flanges and has cam surfaces 157 and 158 thereon. Converging retaining fingers 159 and 160 form cam slots 161 and 162 to either side of the cam 156 respectively. The cam 80 slots 161, cam surfaces 157 and the retaining fingers 159 are adapted to coact with pins 163 secured in the guides 136. The cam surface 158, retaining fingers 160 and the cam slots 162 are adapted to coact with a 85 second pin 164 secured to the guides 136 directly below the pin 163.

When vertical movement is imparted to the shaft 135 and the die carrier, the pin 163 contacts the upper end of slot 161. Further downward movement of the shaft 135 rocks the die carrier about the pin 163, the bottom of the slot acting as the fulcrum and the retaining finger 159 holding the parts in engaged relation. This part of 90 the movement causes the cam 156 to enter the space between the pins 163 and 164, and also forces the cam surface 158 into contact with the pin 164 in such manner as to 95 guide the same into the slot 162. Further 100 movement causes the bottom of the slot 162 to contact the pin 164 which is held by the retaining finger 160. At this stage of the movement the die carrier ceases to rotate about the pin 163 and starts to rotate about 105 the pin 164. Upon further movement of the shaft in a downward direction, the pin 164 acts as the center of rotation and completes the half revolution of the die carrier. The printing face of the die is now 110 turned down immediately over the material, and a slight further movement is necessary to cause the impression to be made after which the action described again takes place but in reverse order to return the die into contact 115 with the ink pad.

The die head 137 is preferably formed integrally with the main frame of the machine, as by being connected thereto by an overhanging neck 170.

Means are provided whereby the ink pad is held and ink conducted thereto. Thus an ink distributing plate 171 is held in place to form the bottom of ink reservoir 172 by screws 173. The ink pad 23 is removably held by retaining lips 174 formed on the plate 171. The ink is adapted to be fed from containers 175 having removable filler caps 176. The containers are secured in the upper wall of the reservoir as by threaded tu- 130

1
bular connections 177. The flow of ink is controlled as by needle valves 178 in the tubular connections. The distributing plate has distributing grooves 179 therein coincident with holes 180 leading to the upper surface of the inking pad. In this manner the ink is evenly distributed over the entire surface of the pad to keep it thoroughly saturated therewith.

10 To compel the follower 105 and the roller 108 to closely follow the surface of the cam when it enters the depression 102 a rotatable cam plate 185 has a retaining cam 186 integrally formed therewith. The retaining cam has downwardly sloping surface 187 concentric surface 188 and upwardly sloping surface 189. The surfaces 187, 188 and 189 closely conformed to the path of the roller 108. The plate 185 has a hub 190, having a bore 191 therein through which the drive shaft 30 passes. The plate has driving connections by means of a key 192 secured in the shaft and coacting with a keyway 193 in the hub. A set screw 194 threaded into the hub 190 holds the plate against lateral movement. A second roller 195 is journaled about the stud 109 and is held between the head 196 thereof and outer surface of the follower. The roller 195 is thus made to act in conjunction with the roller 108, and follow the surfaces 187, 188 and 189 to effectively hold the follower to the path of travel in the depression 102 of the cam 95. The motion of the die carrier is thus prevented from being irregular and insures the making of a perfect impression.

For fixing the impression made by the die on the material, I prefer to employ a fixing member utilizing the properties of heat. Thus the fixing member comprises a heater head 200 having an impression contact face 201. An electrical resistance member 202 is received within the head and has connection by a flexible conductor 203 with a current controlling rheostat 204 operable by a lever 205. An electrical conductor 206 is adapted to convey current to the rheostat.

The fixing member is so actuated as to have the face 201 thereon contact the material during the interval when the die carrier is held in the raised position. Therefore a pair of arms 210 are formed on the heater head 200, which are integrally connected to a hub 211, in which a rock shaft 212 is secured. The shaft 212 is journaled in bearings 213 in the main frame and is held against endwise movement by cotter pins 213.

The hub 211 further has an arm 214 integrally formed therewith having a fork 215 at its outer end. A roller 216 is received between the tangs of the fork 215 and is journaled on a pin 217. The roller is adapted to coact with a cam 220 so formed as to actuate the fixing member while the die carrier is stationary at the upper part of the

die head. The cam has a high concentric portion 221, downwardly sloping portion 222, low concentric portion 223 and upwardly sloping portion 224 which form a depression 225, which the roller 216 is adapted to enter. The cam has a hub 226 thereon having a bore 227 through which the drive shaft 30 passes. Driving connection is had with the shaft as by a key 228 therein coacting with a keyway 229 in the hub. A set screw 230 threaded into the hub, contacts the drive shaft and holds the cam in position. One of the arms 210 has an extension 231 on which a counterweight 232 is adjustably held in position by a set screw 233. The weight of the fixing member is thus counter-balanced and at the same time pressure exerted thereby is regulated.

To avoid injury to the die and fixing member and their actuating mechanisms I prefer to construct the material support 20 in such manner as to permit a slight yielding thereof. Thus the support comprises platen 235 having a stem 236 integrally formed therewith. The stem has vertical movement in a bore 237 in the table 238 integrally connected to the main frame by a neck 239. The lower end of the bore is threaded as shown at 240 to receive a screw plug 241. A spring 242 is received between the stem and the screw plug and provides means whereby the platen is supported. The platen is held against rotary movement as by the end 243 of a set screw 244 coacting with a keyway 245 in the stem and threaded into the table.

The platen is adapted to be readily removable for replacement by variously shaped and other sizes thereof. Therefore a portion of the bore 237 is formed by a removable block 250 held in a slot 251 by a tie rod 252 passing through holes 253 in the table, and a hole 254 in the block. The tie rod has a head 255 and a threaded end 256 about which a thumb nut 257 is received. The block is thus adapted to be clamped in the slot 251 by drawing up on the thumb nut, there being sufficient elasticity in the portions of the table to either side of the slot to permit the clamping action to take place. The screw plug 241 may adjust the tension of the spring 242 and thus control the pressure by which the impression is made, also various thicknesses of material are thus automatically taken care of.

In operation the material to be marked is placed on the platen 235. The operator depresses the treadle 87 which permits engagement of the clutch 68 with the driving pulley 36, thereby rotating the drive shaft 30. The cams 95, 186, and 220 are so mounted on the drive shaft in relation to one another as to actuate either the die carrier or the fixing member when the other is held stationary at its upper limit of travel. When

rotation is imparted to the drive shaft the die is drawn out of contact with the inking pad 23 and in the course of its downward movement is turned over, after which it is forced into contact with the upper surface of the material, thus forming an imprint thereon. The face of the die is immediately withdrawn from the material and returned to its position in contact with the inking pad in the upper part of the die head. After the impression has been made, the fixing member is brought down into contact with the material to fix the impression made. The cam 220 actuates the fixing member through the medium of the roller 216, fork 215, hub 211 and arms 210. The roller enters the depression 225, the low concentric portion 223 of which determines the duration of contact of the heated surface 201 with the material. For goods of average weight the length of contact is usually five seconds. After the contact is made and the impression fixed and driven into the material the cam 220 returns the heater head to its upper position in the neck 170. The material is then ready to be removed from the support and the operation indefinitely repeated on succeeding pieces of material. It has been found by experience that the drive shaft should rotate at such speed as will complete one cycle of operation of the machine in ten seconds time, and also that five seconds contact of the heater head with the material is sufficient to thoroughly fix the impression and drive it into the goods in a satisfactory manner.

To vary the duration of contact of the fixing member with the material for varying qualities and thicknesses thereof cams similar to cam 220 may be substituted therefor, having the low concentric portion 223 either shorter or longer depending as to whether it is desired to reduce or increase length of application. The drive shaft is readily enabled to be withdrawn by removing the bearing 32 by loosening set screw 34. The shaft may then be withdrawn after the driving pulley has been removed therefrom and the set screws in the hubs of the cams loosened. Other cams may be in this way substituted for the one illustrated. In similar manner other cams having longer or shorter depressions may be substituted for the cam 95, for actuating the die carrier, and thus regulate the length of time that the die is in contact with the material, which in turn governs the depth of penetration of the ink.

If the material to be marked is of such a nature and size as to enable the operator to place the same on the yieldable support with sufficient rapidity, the treadle may be held in a depressed position, thus giving a constant rotation to drive shaft and actuating the die carrier and the fixing member alternately, in a continuous manner.

My improved marking machine forms a rapid and automatic means for insolubly marking various materials with no injury thereto or to the mechanism of the machine.

What I claim as new and desire to secure by Letters Patent is:

1. In a marking machine, a yieldable support adapted to hold material to be marked, a reciprocating marking means whereby markings are made on the material by a single operation, an inking means for said marking means and fixing means for instantly indelibly fixing the markings made by said marking means, substantially as set forth and for the purposes specified. 75

2. In a marking machine, a yieldable support adapted to hold material to be marked, an automatically actuated die whereby markings are made on said material, an inking means for said die and an automatically actuated fixing member for instantly driving into and indelibly fixing the impression in the material made by said die, substantially as set forth and for the purposes specified. 85

3. In a marking machine, a frame, a bracket on said frame, a yieldable support mounted on said frame below said bracket, a fixed extension on said frame, a vertically movable die head on said extension, a die fixed in said head and adapted to move vertically, inking means in said head for said die and mounted above said die, said frame having a throat formed between said bracket and said extension, a pivotally mounted fixing member in said extension adapted to be actuated after the operation of said die, actuating means for said die and said fixing member whereby one of the said members is adapted to move into inoperative position and the other into operative position both simultaneously, and driving means for said actuating means, substantially as set forth and for the purposes specified. 95

4. In a marking machine, a die, inking means, heating means, a yieldable support comprising a platen, a stem formed on said platen, a table, a bore in said table in which said stem is received, a screw plug in the other end of said bore, a spring received in said bore between said screw plug and said stem, a slot radial to said bore, a block received in said slot having a surface thereon to form a continuation of the walls of said bore, a tie rod for clamping said block in said slot, a keyway in said stem, and a screw in said table adapted to coact with said keyway, whereby said platen and stem is held against rotary movement. 115

5. In a marking machine, a yieldable support, an automatically actuated die, a heating means, an inking means for said die comprising a reservoir, a perforated plate forming the lower wall of said reservoir, a 130

6
5 pad secured below said plate, a container, a connection between said container and said reservoir, regulating means in said connection and distributing means forming connection between said plate and said pad.

6. In a marking machine, a frame, a yieldable support thereon adapted to hold material to be marked, a die, a carrier therefor, guides in said frame for said carrier, an inking pad for inking said die, and actuating means whereby said die is first caused to contact said ink pad and afterwards to contact the material on said yieldable support and comprising a drive shaft, bearings in said frame for said shaft, a cam releasably mounted on said shaft, said cam having a depression therein, a follower, a bearing in said frame for said follower, a roller rotatably mounted in said follower, a rockable lever, a connecting rod connecting said rockable lever and said follower, a bearing for said rod, an adjustable collar on said rod, a spring about said rod received between said last named bearing and said 20 adjustable collar whereby said follower is urged towards said cam, said rockable lever having one end pivoted to said frame, a cross shaft secured to the other end of said rockable lever, a shaft about which said 25 die carrier is journaled, slots in which said shaft has vertical movement, links connecting said last named shaft to said cross shaft, guides for said carrier in said frame, flanges on said die carrier, cams on said flanges, retaining fingers to either side of said cams, 30 said cams and fingers having cam slots therebetween, pins in said guides adapted to coact with said cam slots on one side of said cams to form a temporary center of rotation for said die carrier, additional pins in said guides adapted to coact with said cam slots on the other side of said cams to 35 form a second temporary center of rotation for said carrier.

45 7. In a marking machine, a yieldable support, an automatically actuated die, a heating means, an inking means for said die comprising a reservoir, a plate forming the lower wall of said reservoir, a pad secured below said plate, a container, tubular connection between said container and said reservoir, regulating means in said tubular connection, distributing grooves in said plate, and apertures in said plate forming connection between said distributing grooves and said pad.

50 8. In a marking machine, a frame, a support thereon adapted to hold material to be marked, a die whereby imprints are made on

the material held on said support, inking means for said die, a fixing member, means embodied in said fixing member whereby the impression made by said die is caused to alter chemically, and actuating means for said fixing member comprising arms on said fixing member, a hub on said arms, a rockable shaft secured in said hub, bearings in said frame for said shaft, a cam, a follower on said hub adapted to coact with said cam, an extension on one of said arms, a counter-weight adjustably secured on said extension whereby said follower is held in contact with said cam, a drive shaft to which said cam is releasably secured, bearings for said shaft in said frame, and means for driving said shaft.

9. In a marking machine, a frame, a yieldable support mounted in said frame, a die head on said frame, a die operative in said head adapted to make impressions, means for inking said die, a fixing member for fixing impressions made by said die, means for actuating said die and said fixing member, comprising a plurality of cams, followers coacting with said cams, and mechanical connections between said die and fixing member and said followers, a drive shaft on which said cams are releasably mounted, a loose pulley journaled on said shaft, a clutch between said pulley and said shaft, comprising a hub endwise slidable on said shaft, pins in said hub, pins in said pulley, said last named pins adapted to contact said first named pins when said endwise slidable hub is moved towards said pulley, a spring between said frame and said hub, whereby said hub is urged toward said pulley, a plunger, bearings in said frame for said plunger, a spring about said plunger, whereby the same is urged toward said hub, a groove in said hub, a cam surface in said groove adapted to engage said plunger, whereby said pins on said hub is selectively held out of engagement with said pins on said pulley, a treadle and a connecting rod between said treadle and said plunger.

10. In a marking machine, a support adapted to hold material to be marked, a die whereby markings are made on the material, inking means for said die, an automatically actuated fixing member for driving into and indelibly fixing the impression into the material made by said die and means for automatically governing the length of time of the application of the fixing member to the marking.

EDWARD G. MEYERS.
